US00D878538S

(12) **United States Design Patent** (10) Patent No.: **US D878,538 S**
Mecker et al. (45) Date of Patent: **** Mar. 17, 2020**

(54) **DISPENSER**

- (71) Applicant: **S. C. JOHNSON & SON, INC.**, Racine, WI (US)
- (72) Inventors: **Alex Mecker**, Chicago, IL (US); **Peter Borowski**, Lake Bluff, IL (US); **Nick Rees**, New York, NY (US)
- (73) Assignee: **S. C. Johnson & Son, Inc.**, Racine, WI (US)
- (**) Term: **15 Years**
- (21) Appl. No.: **29/708,159**
- (22) Filed: **Oct. 3, 2019**

Related U.S. Application Data

- (63) Continuation of application No. 29/638,730, filed on Feb. 28, 2018.
- (51) **LOC (12) Cl.** **23-04**

CLAIM

The ornamental design for a dispenser, as shown and described.

DESCRIPTION

FIG. 1 is an isometric view of a top and front side of a dispenser; and,

FIG. 2 is a top plan view of the dispenser of FIG. 1. The broken lines are included for the purpose of illustrating portions that form no part of the claimed design. The dash-dot-dash lines are included for the purpose of illustrating boundary lines and form no part of the claimed design.
